PRESSURE BAILER

Filed Nov. 7, 1932

UNITED STATES PATENT OFFICE

RICHARD A. LEAHY, OF LONG BEACH, CALIFORNIA, ASSIGNOR TO LEAHY-MCNEELY CO., LTD., OF LONG BEACH, CALIFORNIA, A CORPORATION OF CALIFORNIA

PRESSURE BAILER

Application filed November 7, 1932. Serial No. 641,597.

This invention relates to pressure bailers. Bailers of this type utilize the pressure in a well to charge the bailer. They are usually constructed with a chamber within the bailer which is at a pressure below the well pressure. The pressure in the chamber is usually atmospheric pressure and is maintained by employing a valve between the sand chamber of the bailer and the air chamber. When the bailer is at the bottom of the well, this valve is suddenly opened and the well pressure causes an in-rush of the material which is to be bailed.

The general object of this invention is to simplify the construction of bailers of this type and to provide a construction which will avoid the necessity for employing a valve for sealing the air chamber; and also utilizing substantially the entire volume of the chamber for carrying effective load.

In the present bailer, the air chamber is sealed by means of a frangible disc below which a dart is provided mounted in the lower end of the bailer and when the bailer strikes the bottom of the well, the dart moves relatively upwardly so as to smash the disc, and when this occurs there is an in-rush of sand through the lower end of the bailer due to the high pressure exerted at the bottom of the well. In this way the bailer charges itself by reason of the well pressure.

One of the objects of my invention is to provide improved means for retaining the sealing disc, and for effecting its replacement, and also an improved construction for the dart which enables it to operate as an effective valve to retain the charge in the bailer under pressure until it is taken from the mouth of the well to be discharged.

The discharging of the bailer is effected by the pressure within it by opening a port in the side of the bailer, or through the bottom opening of the shoe when the dart valve is raised off its seat. In bailers of this type, if the pressure at the bottom of the well is very great, there is danger that the pressure in the bailer load chamber may be so much above atmospheric pressure that the bailer will explode when it reaches the mouth of the well. For this reason, in bailers of this

type, it has been the practice to provide a relief valve which will relieve the internal pressure of the bailer as it approaches the surface. One of the objects of this invention is to provide a simple means for regulating this relief valve so that it can be readily set to enable it to retain greater or lower pressures as may be desired. In this way the rapidity of discharge of the load at the derrick floor can be regulated.

A further object is to provide a mounting for the relief valve which will enable it to be readily cleaned without unscrewing any joints of the bailer.

A further object of the invention is to provide means at the lower end of the bailer, tending to prevent it from becoming "frozen" in tightly packed sand at the well bottom.

One of the difficulties experienced in the operation of a dart or breaking device by impact upon the sand at the bottom of the well, is that unless the lower end of the dart has considerable area, it naturally tends to bury itself in the sand instead of being arrested in its downward movement by the sand. One of the objects of this invention is to construct the lower end of the dart so that while it presents a considerable area sufficient to prevent its burying itself in the sand, this will not obstruct the lower end of the bailer in such a way as to interfere with the effective charging of the same.

Further objects of the invention will appear hereinafter.

The invention consists of the novel parts and combination of parts to be described hereinafter, all of which contribute to produce an efficient pressure bailer.

A preferred embodiment of the invention is described in the following specification, while the broad scope of the invention is pointed out in the appended claims.

In the drawing:

Figure 1 is a side elevation in partial section of a bailer embodying my invention, certain parts being broken away and shown in section; this view indicates the outline of the well hole;

Figure 2 is a vertical section upon an enlarged scale, taken through the lower end of

the bailer about on the line 2—2 of Figure 1, and showing the parts in the relation which they have when the bailer is descending in the well;

5 Figure 3 is a horizontal section upon an enlarged scale taken on the line 3—3 of Figure 1 and passing through the relief valve; Figure 4 is a horizontal section on the line 4—4 of Figure 2, but showing the bailer with 10 the discharge port open at its side;

Figure 5 is a horizontal cross-section on the line 5—5 of Figure 2, and upon an enlarged scale;

15 Figure 6 is a fragmentary view and is a section upon an enlarged scale through the edge of a frangible disc and illustrating another embodiment of the means which may be employed for insuring a tight seal of the disc on its seat;

20 Figure 7 is a plan of the resilient means which I prefer to employ for holding the frangible disc on its seat.

Referring more particularly to the parts, the bailer comprises a casing 1, the upper 25 portion of which is formed into connected sections 2 in which an air chamber 3 is formed, the upper end of the casing being provided with a sub 4 having means for attaching the same to a string of tubing, or if 30 desired, to a bailer head for enabling the bailer to be attached to a sand line.

The lower end of the casing is in the form of a shoe 5 (see Fig. 2) which may be threaded on to the lower end of the bailer body.

35 The lower portion of the bailer casing below the air chamber 3, is provided with an annular seat or shoulder 6 upon which is received a frangible disc 7. This disc may be made of hard and relatively brittle cast iron, 40 or may be formed of any other material which can be readily broken up by impact from below. On the upper face of this frangible disc I provide a gasket 8, which gasket may be a thin disc of cork or similar material 45 cemented to the upper side of the disc. The disc may be held in place in any suitable way; for example, it may be used as a tight plug in the bore. Or any suitable means, preferably resilient means, formed of thin metal, 50 may be employed. This means, in the present instance, is in the form of a thin flat bar 10 which is of slightly larger diameter than the bore 11 of the casing at this point. This enables the bar to be shoved up against the lower 55 face of the disc with its rounded ends engaging against the face of the wall. The disc is preferably slightly tapered toward its edges. If desired, the bar 10 may also be fastened at its center to the center of the disc, in which 60 case it could be employed above the disc.

Access may be had to the interior of the bailer to put the disc and the keeper 10 in position, through a discharge gate or port 12. When the bailer is passed down the well, this 65 discharge opening 12 is held closed by a rotat-

able gate 13 having an opening 14 in it which may register with the opening 12 (see Fig. 4).

Removably mounted in the lower part of the casing, I provide a bushing 15, the upper 70 end of which forms the seat 16 to receive a valve 17 which is formed as a head on a dart 18. The body of this dart is in the form of a stem 19 and extends downwardly and terminates in a plurality of radial wing guides 75 20. Below these two guides the dart has a flat circular head 21 presenting considerable area on its under side. The upper ends of the wings 20 terminate in shoulders 22 for engaging the lower end of the bushing 15 when the dart is driven relatively upwardly by impact with sand at the bottom of the well. The movement however, is sufficient to enable a tapered point 23 on the upper end of the dart to strike the disc 7 and break it. The 80 sudden opening of the air chamber 3 by smashing the disc, causes an in-rush of sand, water and other material at the bottom of the well to the lower end of the shoe. The opening at this point is not restricted in any way by the head 21 by reason of the fact that the lower end of the bushing 15 will hold the head 21 low enough to provide effective flow area for the incoming charge. The valve 17 is carried below a shoulder 19a on the stem 19. 85

The bushing 15 is preferably held in place 90 removably by providing its lower end with a collar 24 held between the lower end of the bailer body and an annular shoulder 25 on the interior of the shoe.

95 The wall of the bailer casing is preferably provided with a relief valve 26 (see Figs. 1 and 3). This relief valve is in the form of a ball or button with a conical or spherical face coming upon a corresponding seat 27 so that the relief valve can open outwardly. This relief valve is held on its seat by an annular spring 28 that is received in an annular groove 29 formed on the exterior of the casing at this point. The tip 30 of this spring 100 engages a transverse groove 31 on the outer face of this valve. The seat 27 for the valve is preferably formed in a bushing 32 (see Fig. 3) which is screwed into a threaded opening 105 in the casing. 110

115 The spring 28 is preferably tapered toward its split point from its butt end 33. If it is desired to provide for adjustment of the force exerted by this spring in holding the valve on its seat, I provide an adjusting stud 34 that may be mounted in any one of a plurality of threaded sockets 35 in the wall of the casing at the groove 29. Figure 3 shows this plug set for the lightest spring force. It is evident however, that if this plug or stud 34 is removed and the spring 28 driven around the casing in the direction in which it tapers, the butt 33 of the spring can be brought into position near the next threaded socket 35. The plug can then be applied to 120 125 130

hold the spring in position and prevent its working away from the valve.

In using bailers of this type, there is a tendency for them to bury their lower ends in the sand so as to become "frozen" which interferes with their being pulled up. In order to provide against this, I provide the lower end of the shoe 5 of the bailer, with a plurality of threaded ports 36 which are normally closed by threaded plugs 37. In using the bailer, any opposite pair, or if desired, all four of these plugs can be removed.

By turning the spring clear of the valve, the valve may be readily removed for cleaning.

In Figure 6 I illustrate a modification of the sealing means for the disc. In this view, 7^a indicates the disc. The sealing means consists of a band 8^a of rubber that is applied tight over the edge of the disc. This forms an effective gasket, and a gasket of this form can readily be made from a short section of inner tubing of a tire or a broad rubber band of suitable diameter. The valve 17 is loose on the stem 19. In the operation of the bailer when it is taking a load the valve 17 will be carried up off its seat by the inflow of material through the bottom of the bailer. If the valve 17 were rigidly attached to the stem, considerable time would elapse before it would fall back and be receded. This would entail the loss of considerable material from the bailer. But, as the valve 17 is loose it does not rise a great distance from its seat and, therefore, it seats promptly at the end of the charging movement of material. This increases the efficiency of the bailer in charging itself.

40 The relief valve 26 is preferably located near the upper end of the bailer and is preferably mounted in a sub 26^a, which affords a thickened wall to receive the valve. The height of this valve should be such that it will always be below the water level in the upper part of the bailer. In this connection, it should be understood that when the load comes into the bailer air is trapped in the upper part of the air chamber and as the 45 relief valve lets down the pressure this trapped air expands and lowers the liquid level in the bailer.

It is understood that the embodiment of the invention described herein is only one of the many embodiments this invention may take, and I do not wish to be limited in the practice of the invention, nor in the claims, to the particular embodiment set forth.

What I claim is:

60 1. In a bailer for bailing deep wells under pressure, the combination of a casing having an air-tight chamber and having an annular shoulder formed therein below the chamber, a frangible disc seating on said shoulder from the lower side, means set in the casing below

the disc for holding the same upon its seat, a valve seat in the form of a bushing, a dart passing through the bushing, a valve on the dart to come upon the valve seat, said dart having its lower end projecting below the lower end of the casing and operating when the bailer is dropped upon the bottom of the well, to force the dart upwardly and break the disc thereby effecting the charging of the bailer through the action of the well pressure at the well bottom, said valve operating to retain the charge under pressure. 70

2. In a bailer for bailing deep wells under pressure, the combination of a casing having an air-tight chamber and having an annular shoulder formed therein below the chamber, a frangible disc seating on said shoulder from the lower side, means set in the casing below the disc for holding the same upon its seat, a valve seat in the form of a bushing, a dart passing through the bushing, a valve on the dart to come upon the valve seat, said dart having its lower end projecting below the lower end of the casing and operating when the bailer is dropped upon the bottom of the well, to force the dart upwardly and break the disc thereby effecting the charging of the bailer through the action of the well pressure at the well bottom, said valve operating to retain the charge under pressure, 80 said casing having a discharge port at the side thereof, above the valve and below the frangible disc, a movable closure for the discharge port mounted on the casing, said discharge port enabling the frangible disc to be passed into the casing to place the same on said annular shoulder. 85

3. In a bailer for bailing deep wells under pressure, the combination of a casing having an air-tight chamber and having an annular shoulder formed therein below the chamber, a frangible disc seating on said shoulder from the lower side, means held in the casing below the disc for holding the same upon its seat, a valve seat in the form of a bushing, a dart passing through the bushing, a valve on the dart to come upon the valve seat, said dart having its lower end

projecting below the lower end of the casing and operating when the bailer is dropped upon the bottom of the well, to force the dart relatively upwardly and break the disc, thereby effecting the charging of the bailer through the action of the well pressure at the well bottom, said valve operating to retain the charge under pressure, said dart having a head at its lower end having considerable area, and having a stem with laterally projecting means for engaging a part of the bailer when the dart moves relatively upwardly, to hold the said lower head of the dart at a considerable distance below the lower end of the casing, thereby providing an 100 105 110 115 120 125 130

effective charging area at the lower end of the bailer.

4. In a bailer for bailing deep wells under pressure, the combination of a casing having an air-tight chamber and having an annular shoulder formed therein below the chamber, a frangible disc seating on said shoulder from the lower side, means set in the casing below the disc for holding the same upon its seat, a valve seat in the form of a bushing, a dart passing through the bushing, a valve on the dart to come upon the valve seat, said dart having its lower end projecting below the lower end of the casing and operating when the bailer is dropped upon the bottom of the well, to force the dart upwardly and break the disc thereby effecting the charging of the bailer through the action of the well pressure at the well bottom, said valve operating to retain the charge under pressure, a relief valve mounted in the casing to open outwardly above the frangible disc, said casing having an annular groove in the outer side thereof adjacent the relief valve and a tapered annular spring mounted in said groove and engaging the outer side of the relief valve.

5. In a bailer for bailing deep wells under pressure, the combination of a casing having an air-tight chamber and having an annular shoulder formed therein below the chamber, a frangible disc seating on said shoulder from the lower side, a valve seat in the casing below the frangible disc, a spring extending transversely across the casing below the frangible disc and engaging the wall of the casing for retaining the disc on said annular shoulder, a valve seat in the form of a bushing, a dart passing through the bushing, a valve on the dart to come upon the valve seat, said dart having its lower end projecting below the lower end of the casing and operating when the bailer is dropped upon the bottom of the well, to force the dart relatively upwardly and break the disc, thereby effecting the charging of the bailer through the action of the well pressure at the well bottom, said valve operating to retain the charge under pressure.

6. In a bailer for bailing deep wells under pressure, the combination of a casing having an air-tight chamber and having an annular shoulder formed therein below the chamber, a frangible disc seating on said shoulder from the lower side, means set in the casing below the disc for holding the same upon its seat, a valve seat in the form of a bushing, a dart

passing through the bushing, a valve on the dart to come upon the valve seat, said dart having its lower end projecting below the lower end of the casing and operating when the bailer is dropped upon the bottom of the well, to force the dart upwardly and break the disc thereby effecting the charging of the bailer through the action of the well pressure at the well bottom, said valve operating to retain the charge under pressure, a relief valve mounted in the casing to open outwardly above the frangible disc, said casing having an annular groove in the outer side thereof adjacent the relief valve and a tapered annular spring mounted in said groove and engaging the outer side of the relief valve.

7. In a bailer for bailing deep wells under pressure, the combination of a casing having an air-tight chamber and having an annular shoulder formed therein below the chamber, a frangible disc seating on said shoulder from the lower side, a valve seat in the casing below the frangible disc, a spring extending transversely across the casing below the frangible disc and engaging the wall of the casing for retaining the disc on said annular shoulder, a valve seat in the form of a bushing, a dart passing through the bushing, a valve on the dart to come upon the valve seat, said dart having its lower end projecting below the lower end of the casing and operating when the bailer is dropped upon the bottom of the well, to force the dart relatively upwardly and break the disc, thereby effecting the charging of the bailer through the action of the well pressure at the well bottom, said valve operating to retain the charge under pressure.

8. In a bailer for bailing deep wells under pressure, the combination of a casing having an air-tight chamber, a frangible member mounted in the bailer for sealing the lower end of the air chamber, said casing having a valve seat below the air chamber, a dart with a valve normally resting on said seat, said dart having its lower end projecting at the lower end of the casing and operating when the bailer is dropped upon the bottom of the well to force the dart relatively upwardly to break the frangible member and thereby effect the charging of the bailer through the action of the well pressure, said valve operating to retain the charge under pressure.

9. In a bailer for bailing deep wells under pressure, the combination of a casing having an air-tight chamber above, a frangible member mounted in the casing for sealing the lower end of the air-tight chamber, said casing having a valve seat below the frangible member, a dart having a stem and a valve loose on the stem and seated on the valve seat, said dart having its lower end projecting below the lower end of the casing and operating to break the frangible member when the bailer is dropped upon the bottom of the well,

thereby effecting the charging of the bailer
through the action of the well pressure, said
valve operating to retain the charge under
pressure.

5 Signed at Los Angeles, California, this 31st
day of October, 1932.
